UNITED STATES PATENT OFFICE.

JOHN BABIS, JR., OF PHILADELPHIA, PENNSYLVANIA.

STYLUS-HOLDER FOR TALKING-MACHINES.

1,290,044.

Specification of Letters Patent.

Patented Jan. 7, 1919.

Application filed October 30, 1917. Serial No. 199,289.

To all whom it may concern:

Be it known that I, JOHN BABIS, Jr., a citizen of the United States, residing in Philadelphia, Pennsylvania, have invented 5 certain Improvements in Stylus-Holders for Talking-Machines, of which the following is a specification.

The object of my invention is to provide 10 efficient means whereby a worn stylus can be discharged from the stylus holder of a phonograph, a fresh stylus presented in place of the same, and said fresh stylus firmly gripped and retained in proper position in said stylus holder.

15 This object I attain in the manner hereinafter set forth, reference being had to the accompanying drawings, in which—

Figure 1 is a face view on an enlarged scale of the sound box of a phonograph 20 equipped with stylus changing devices in accordance with my invention;

Fig. 2 is a side view of the same looking in the direction of the arrow α , Fig. 1;

Fig. 3 is a face view of the stylus holder 25 with some of the parts in a different position from that represented in Fig. 1;

Fig. 4 is a view partly in plan and partly 30 in transverse section, on the line 4—4, Fig. 1;

Fig. 5 is a similar view taken on the line 5—5, Fig. 3;

Fig. 6 is a section on the line 6—6, Fig. 1;

Fig. 7 is a section on the line 7—7, Fig. 3;

Fig. 8 is a vertical sectional view of the 35 stylus reservoir and its delivery chute;

Fig. 9 is a view partly in plan and partly in transverse section on the line 9—9, Fig. 8;

Fig. 10 is a view partly in plan and partly 40 in section on the line 10—10, Fig. 8, and

Fig. 11 is a view partly in elevation and partly in section on the line 11—11, Fig. 1.

In the drawing, 1 represents the casing of the sound box of a phonograph, upon which 45 the stylus reservoir 2 is fixedly mounted, a stylus-directing chute 3, the latter terminating in the flaring upper end of a tubular stylus holder 20 which is mounted upon the usual stylus lever 21 of the machine, as shown in Figs. 1 and 2. The reservoir 2 contains the stylus supply indicated at 22, the same being pressed downwardly in said reservoir by means of a plunger 23 acted upon by a spring 24. Mounted

55 at the bottom of the stylus reservoir and free to reciprocate across the same is a selector slide 25, to which reciprocating movement may be imparted from a lever 26 which engages an ear 27 on the selector slide and is provided with a push button 28 whereby 60 it can be readily manipulated, a coiled spring 29 serving to normally maintain the lever 26 in the position shown in Fig. 2, that is to say, with the selector slide 25 fully retracted and the lowermost stylus in 65 the reservoir 2 occupying a position in a transverse slot 30 in the selector slide, as shown in Fig. 8.

At the bottom of the reservoir 2 is a forwardly projecting flange 31 from which 70 depends the chute 3, said flange having therein a slot 32 with opposite pointed ends, as shown in Fig. 10.

When the selector lever 26 is depressed 75 the selector slide 25 is caused to move forwardly and the stylus occupying the slot 30 in said slide is brought into line with the slot 32 in the flange 31 of the reservoir and drops through said slot into the chute 3, the pointed end of the stylus passing 80 through the corresponding end of the slot and the butt end of the stylus being retained by the opposite pointed end of said slot so as to upend the stylus and feed it point down through the chute 3 and into 85 the upper flaring end of the holder 20 through which it likewise passes point down until it reaches the adjusting, gripping and retaining mechanism at the lower end of 90 said holder.

The adjusting, gripping and retaining mechanism is as follows:

In a boss 33 on the face of the holder 20 is free to move laterally a cam slide 34 which is moved in one direction by a spring 95 35 and in the other direction by a lever 36, said spring 35 being interposed between one end of the boss 33 and the head 37 of an adjusting plate 38 which is mounted upon and moves with the cam slide 34, and projects forwardly below the lower end of 100 the tubular stylus holder 20, as shown in Figs. 1 and 3, said projecting portion of the adjusting plate having therein a V-shaped slot 39 with the mouth of the V at 105 the outer end of the plate, as shown in Figs. 6 and 7.

The lever 36 is normally free from contact

with the head 37, so that it will exert no restraining influence upon the freedom of vibration of the stylus lever.

When the cam slide 34 is moved in one direction across the tubular stylus holder 20 its cam 40 is freed from contact with the stylus which is in operative position in the lower part of said holder, as shown in Fig. 5, consequently said stylus is free to drop from the holder and to be replaced by a fresh stylus delivered point down from the feed chute 3, movement of the cam slide 34 from the position shown in Fig. 5 to that shown in Fig. 4 causing said stylus to be firmly clamped in the lower portion of the holder, as shown in Fig. 4.

When the cam 40 releases its hold upon the worn stylus and permits the latter to drop from the holder 20 the V-shaped slot in the adjusting plate 38 has, as shown in Fig. 6, not advanced far enough to interfere with the free discharge of said worn stylus, but, by the time the fresh stylus has dropped into the holder the slot 39 will have advanced to the position shown in Fig. 7 and the tapering point of the stylus will engage the walls of the slot 39 and said stylus will thus be retained in its proper position of adjustment in the holder 20, the gripping of the fresh stylus by the cam 40 on the retraction of the slide 34 preventing the release of the stylus as the walls of the slot 39 are withdrawn from contact with the tapered end of said stylus.

I may, in some cases, use an unslotted adjusting plate which arrests the downward movement of the fresh stylus by contact with the point of the same, but the slotted adjusting plate is preferred because it effects the desired adjustment of the stylus without risk of dulling the point of the same.

Proper action of the lever 36 upon the cam slide 34 is effected on each operation of the stylus selecting lever 26 in the following manner: At one end of the pivot shaft 41 of the lever 26 is a segmental rack 42 which meshes with a pinion 43 free to turn upon a pin 44 which projects from one side of the stylus reservoir 2, as shown in Fig. 11. This pinion has a ratchet toothed hub 45, the teeth of which engage with those of a ratcheted hub 46 on a cam disk 47 likewise free to turn on the pin 44 and also to slide longitudinally thereon, said disk being normally retained in the position shown in Figs. 2 and 11 by means of a coiled spring 48 contained in the recessed face of the cam disk 47 and interposed between the base of said recess and a plug 49 which bears against the head of the pin 44, as shown in Fig. 11. When therefore the lever 26 is depressed or moved in the direction of the arrow, Fig. 2, the cam disk 47 will likewise be moved in the direction of the arrow shown thereon and the lever 36 will be operated so as to come into contact with the

head 37, and then to impart forward movement to the cam slide 34, the cam-actuated arm of the lever 36 then dropping onto the succeeding cam, as shown in Fig. 2, preparatory to further movement of the cam disk in the direction of the arrow.

On backward movement of the lever 26 the ratchet faces of the hubs 45 and 46 will act as cams to cause the cam disk 47 to be moved outwardly on the pin 44 without rotation, the spring 48 causing the inward movement of the disk and reengagement of the ratchet teeth as soon as the hub 45 has completed the partial turn due to the backward movement of the lever 26. On each operation of said lever 26, therefore, a selected stylus will be delivered by the selector slide 25 to the slotted upper end of the delivery chute 3, will be upended and delivered point first from said chute 3 to the holder 20 and will pass through the latter until its forward movement is arrested by the adjusting plate 38, the used stylus being discharged in advance of the fresh one and the latter being then firmly gripped by the cam slide 34 in proper position for engagement with the record.

In order to prevent any back movement of the fresh stylus under the pressure of the record a retainer plate 50 carried by the cam slide is, as shown in Fig. 1, inserted behind the fresh stylus, as the cam slide moves to the gripping position shown in Fig. 4; and the parts remain in this position as long as the stylus is in action, the operations being repeated as soon as each worn stylus is discharged and a fresh one is inserted in place of the same.

A weight 51 is applied to one arm of the stylus lever 21, as shown in Fig. 1, in order to counterbalance the weight, on the other arm of said lever, of the stylus holder and of the parts carried thereby, free movement of the stylus by the record being thus permitted and deadening of the sound of the record thereby prevented.

I claim:

1. The combination of the stylus holder, a stylus gripping and releasing device comprising a cam slide, means for guiding the same for movement in a direction transverse to the axis of the stylus, means for moving the same back and forth in said guide, and an adjusting device carried by and movable with said cam slide, said adjusting device having a member projecting below the stylus holder and having a V-shaped slot therein for arresting downward movement of the stylus through the holder when the cam slide is in the releasing position.

2. The combination of the stylus holder, a stylus gripping and releasing device, a lever for acting on said gripping device, a cam disk for acting on said lever, a stylus

selecting lever, a cam-driving device movable in both directions with said selecting lever, a ratchet connection between said driving device and said cam disk, and means for permitting longitudinal movement of the cam disk and separation of said ratchet mechanism on the backward movement of the driving device.

3. The combination of the stylus holder, a stylus gripping and releasing device, a lever for acting on said gripping device, said lever being normally free from contact with said gripper, a cam disk for acting on said lever, a stylus selecting lever, a cam-driving device movable in both directions with said selecting lever, a ratchet connection between said driving device and said cam disk, and means for permitting longitudinal movement of the cam disk and separation of said ratchet mechanism on the backward movement of the driving device.

4. The combination of the stylus holder, a stylus gripping and releasing device, a cam disk for operating said gripping and releasing device, a selector lever, a rack movable therewith, a toothed pinion engaging said rack, a ratchet hub on said pinion, a ratchet hub on the cam for engagement with that on the pinion, and a spring for normally pressing said ratchet members into engagement but permitting longitudinal movement one in respect to

the other when the pinion is turned backward.

5. The combination of the transmitting lever pivotally mounted upon the sound box, a stylus holding, gripping and releasing device on the forward arm of said lever, a stylus reservoir mounted on the face of the sound box, a stylus selecting slide, a directing chute for the stylus, means for effecting joint and simultaneous operation of said stylus selecting slide and said stylus gripping and releasing device, and a counterbalance weight on that arm of the transmitting lever between the pivot and the diaphragm of the sound box.

6. The combination of the stylus holder, means for feeding styli thereto in succession, a stylus gripping and releasing device on said holder, and a retainer plate presenting a flat surface in a plane transverse to the axis of the stylus, said plate being movable with said gripping and releasing device so as to be inserted behind the fresh stylus as the gripping device moves to gripping position and to be carried out of the path of the incoming stylus as the gripping device is moved to releasing position, said plate opposing a direct resistance to inward thrust upon the stylus.

In testimony whereof I have signed my name to this specification.

JOHN BABIS, JR.
